UNITED STATES PATENT OFFICE.

MARK MEREDITH, OF PHILADELPHIA, PENNSYLVANIA.

DESIGN FOR A CAKE, &c.

SPECIFICATION forming part of Design No. 24,788, dated October 22, 1895.

Application filed September 3, 1895. Serial No. 561,354. Term of patent 3½ years.

To all whom it may concern:

Be it known that I, MARK MEREDITH, a citizen of the United States, residing at the city of Philadelphia, in the county of Philadelphia and State of Pennsylvania, have invented and produced a certain new and original Design for a Cake or Similar Article, of which the following is a specification.

The leading feature of my design consists of a cake or the like with the representation of a bloomer-attired personage indented into or pressed onto the body of the cake and mounted on a two-wheeled vehicle, the body of the cake as to shape or configuration being in the form of a truncated cone, with the corners curved and the upper portion of the cone arched, thereby disclosing portions of the wheels of the vehicle at the corners thereof and the mounted personage within the arch of the conical body of the cake.

In the accompanying drawings, Figure 1 is a top or plan view of a cake or the like embodying the features of shape and configuration, as well as ornamentation, of my design; and Fig. 2 is a sectional view on the line xx of Fig. 1 of the cake or the like, showing the design of my invention indented into the body of the article.

Referring to the drawings, A is the shape or configuration of the body of the cake, having the arched top portion a , curved corner portions a' and a'' , slanting straight sides a^3 and a^4 , and straight horizontal bottom portion a^5 .

B is a personage in bloomer attire, constituting part of the ornamentation, mounted on a two-wheeled vehicle C, with the position of the personage on said vehicle represented as being in the act of pedaling the vehicle.

The concentric line ornamentations d serve to indicate rotation of the respective wheels of the vehicle.

What I claim as new, and desire to secure by Letters Patent, is—

The design for a cake or similar article, substantially as illustrated and described.

In testimony whereof I have hereunto set my signature in the presence of two subscribing witnesses.

MARK MEREDITH.
